UNITED STATES PATENT OFFICE.

HERMAN C. DOMAN, OF OSHKOSH, WISCONSIN.

WASHING-MACHINE MECHANISM.

1,240,426.

Specification of Letters Patent. Patented Sept. 18, 1917.

Application filed March 29, 1913. Serial No. 87,400.

To all whom it may concern:

Be it known that I, HERMAN C. DOMAN, a citizen of the United States, and resident of Oshkosh, in the county of Winnebago and 5 State of Wisconsin, have invented new and useful Improvements in Washing-Machine Mechanism, of which the following is a description, reference being had to the accompanying drawings, which are a part of this 10 specification.

This invention relates to improvements in washing machine mechanism.

It is one of the objects of the present invention to provide a washing machine mechanism for changing a rotary movement of a 15 driving shaft into a rocking and reciprocal movement of a pounder shaft.

A further object of the invention is to provide a washing machine mechanism having a horizontal driving shaft and a vertical pounder in which the parts coact to permit the easy disengagement of the driving means 20 from the driven means.

A further object of the invention is to provide a washing machine mechanism in which a yielding connection between the horizontal and the vertical shafts performs the two fold function of transmitting a 25 rotary movement into a rocking and reciprocal movement and also serves to hold two shaft sections separably connected together.

A further object of the invention is to provide a washing machine mechanism which is of simple construction, is strong 30 and durable and is well adapted for the purpose described.

With the above and other objects in view the invention consists of the improved washing machine mechanism and its parts and 35 combinations as set forth in the claims, and all equivalents thereof.

In the accompanying drawing in which the same reference characters indicate the same parts in all of the views:

40 Fig. 1 is a top view of a portion of a washing machine on which the improved mechanism is mounted, part of the mechanism being shown in section;

Fig. 2 is a vertical sectional view thereof 45 taken on line 2-2 of Fig. 1;

Fig. 3 is a front detail view of the washing machine and mechanism;

Fig. 4 is an end detail view of one of the shafts; and

50 Fig. 5 is a detail view of the cross head. Referring to the drawing the numeral 5

indicates the tub or receptacle which is provided with a top portion 6 and a hinged cover or portion 7. The receptacle 5 is preferably formed of metal and is of rectangular shape and the hinged cover 7 is adapted to be opened to remove or place clothes within the tub. An angular bracket 8 mounted on the top and side portions of the tub is provided with an upper horizontally extending bearing 9 and a vertically extending slotted side portion 10. A horizontal driving shaft section 11 extends through the upper bearing 9 and on its outer end portion is provided with a sprocket wheel 12 and a cranked arm 13. The cranked arm 13 is provided for manually rotating the shaft and the sprocket wheel is used for transmitting motion to a fly wheel 14 which is journaled on a short stud shaft 15 engaging the slotted portion of the bracket 8. This stud shaft 15 is formed with a collar 16 which bears against the bracket on each side of the slot and a nut 17 threaded on the inner end of the stud shaft 80 and bearing against the inner face of the bracket adjustably clamps the shaft in position. A small sprocket wheel or pinion 18 also journaled on the stud shaft is attached to and turns with the fly wheel and has a chain connection 19 with the sprocket wheel 12 of the driving shaft 11 and is driven thereby. The elongated slot in connection with the stud shaft provides for taking up 85 wear of the sprocket chain by increasing the distance between the two shafts. 90

The inner end of the driving shaft 11 terminates at a point to permit the hinged cover to be swung to open position without striking against the said shaft and has 95 mounted thereon a recessed clutch member 20. The recess 21 of said clutch member is of rectangular form and is slightly tapering longitudinally with relation to the shaft to permit the easy entrance of the complementary clutch member 22. The clutch member and the sprocket wheel also serve as collars on the driving shaft and are positioned to bear against the opposite end portions of the upper bearing 9 to prevent endwise 100 movement of said shaft. This last mentioned clutch member is mounted on the outer end of a supplemental driving shaft section 23 which is in axial alinement with the driving shaft 11 and is rotated thereby. 105 The supplemental driving shaft 23 is journaled in the upper bearing 24 of a bracket 110

25 which is mounted on the hinged cover or portion and is moved therewith. The bracket 25 extends to a point adjacent the central portion of the cover and is provided with two upstanding guide rods 26 on which is slidably mounted a reciprocal cross head 27. A reciprocal pounder or work shaft 28 having a pounder 29 within the tub and mounted on the lower end of the shaft extends vertically through the hinged cover and the bracket and between the upstanding guide rods and at its upper end is rockingly connected to the cross head 27 by a horizontally extending arm 30. The inner or hub end of the arm extends into the elongated recess 31 of the cross head 27 and the upper end portion of the pounder shaft extends revolubly through the cross head and through the interposed hub portion of the arm and is pinned to said arm. This construction permits the arm to rock the pounder shaft while it is being reciprocated vertically. The outer end portion of the arm 30 is formed with a spherical end or ball 32 which enters a socket 33 provided in the outer end of an arm 34 pivotally mounted on the inner end of the supplemental shaft 23. The pivotal arm 34 is formed with a recess 35 into which extends an arm 36 which is mounted fast on the inner end portion of the supplemental shaft 23 by the same pin 37 which pivotally connects the arm 34 to said shaft. A coiled spring 38 interposed between the two arms 34 and 36 and extending into a recess 39 performs the twofold function of holding the socketed member in engagement with the ball shaped end of the pounder shaft arm and also to yieldingly hold the two clutch members operatively in engagement with each other. It will be noted that the distance between the complementary clutch member 22 and the arm 36 is greater than the length of the bearing 24 to permit the reciprocation of the supplemental shaft in engaging and disengaging the complementary clutch members.

The bearing 23 is formed in two parts and the space 23' between the parts permits a washer 40 to be mounted on the shaft and which washer bears inwardly against a transverse pin 41 extending through the shaft.

A clutch control push and pull member 42 slidably extending through a casing 43 covering the portions of the mechanism is provided with a bifurcated wedge portion 44 on its lower end which straddles the supplemental shaft between the washer and one of the parts of the bearing 24 and forces said supplemental shaft inwardly against the pressure of the coiled spring 38 and disengages the clutch members. A coiled spring 44' having its upper end connected to the casing and its lower end connected

to the control member holds the said control member in its upper position when the two shafts are in clutching engagement. The pivotal arm 34 and the coiled spring 38 compensate for the varying distance between the said pivotal arm and the pounder shaft during the reciprocal and rocking movement of said shaft. 70

While a cranked handle is shown for turning the drive shaft it is to be understood that the shaft may be rotated by power means if desired. 75

In operation the turning of the crank arm will reciprocate and rock the pounder shaft and the fly wheel connection will tend to steady and give a more uniform motion to the parts. If it is desired to raise the cover of the tub it is only necessary to push downwardly on the control member to separate the clutch member and the cover may then be swung upwardly to open position. After the cover is swung to closed position and it is desired to further operate the pounder the clutch member is pulled upwardly to permit the spring of the pivotal arm to force the slideable clutch member into engagement with the other clutch member and the parts may then be operated as before by turning the hand crank. 85 90

From the foregoing description it will be seen that the washing machine mechanism is of very simple construction and is well adapted for the purpose described. 95

What I claim as my invention is:

1. A washing machine mechanism, comprising a work shaft, a two part driving shaft extending at an angle with relation thereto, a resilient and cranked connection between the driving shaft and the work shaft, clutch members carried by the respective parts of the two part shaft for operatively connecting the two parts of the shaft together, and means for disconnecting said shaft parts. 100 105

2. A washing machine mechanism, comprising a work shaft, a two part driving shaft extending at an angle with relation thereto, clutch members operatively and detachably connecting the two parts of the two part shaft together, a resilient and cranked connection between the driving shaft and the work shaft for transmitting motion from one shaft to the other and for yieldingly holding the clutch members in engagement with each other, and means for disengaging one clutch member from the other. 110 115 120

3. A washing machine mechanism, comprising a work shaft, a two part driving shaft extending at an angle with relation thereto, clutch members operatively and detachably connecting the two parts of the two part shaft together, a resilient and cranked connection between the driving shaft and the work shaft for transmitting 125 130

motion from one shaft to the other and for yieldingly holding the clutch members in engagement with each other, and a wedge shaped member controlling the disengagement of one of the clutch members from the other.

4. A washing machine mechanism, comprising a work shaft, a two part driving shaft extending at an angle with relation thereto, one of said shaft parts having an endwise movement, clutch members mounted on the adjacent ends of the two part shaft to operatively and detachably connect the shaft ends together, a resilient and cranked connection between the endwise movable driving shaft part and the work shaft for transmitting a rotary movement of the driving shaft to a reciprocal and rocking movement of the work shaft and to also maintain the clutch members in engagement with each other, and means for disengaging one clutch member from the other.

5. A washing machine mechanism, comprising a work shaft, a two part driving shaft extending at an angle with relation thereto, one of said shaft parts having an endwise movement, clutch members mounted on the adjacent ends of the two part shaft to operatively and detachably connect the shaft ends together, a resilient and cranked connection between the endwise movable driving shaft part and the work shaft for transmitting a rotary movement of the driving shaft to a reciprocal and rocking movement of the work shaft and to also maintain the clutch members in engagement with each other, and a wedge shaped member controlling the disengagement of one of the clutch members from the other.

6. A washing machine mechanism, comprising a work shaft, a two part driving shaft extending at an angle with relation thereto, one of said shaft parts having an endwise movement, clutch members mounted on the adjacent ends of the two part shaft to operatively and detachably connect the shaft ends together, a resilient and cranked connection between the endwise movable driving shaft part and the work shaft for transmitting a rotary movement of the driving shaft to a reciprocal and rocking movement of the work shaft and to also maintain the clutch members in engagement with each other, and a reciprocal controlling member having a wedge shaped portion for moving the endwise movable shaft part endwise to disengage one clutch member from the other.

7. A washing machine mechanism, comprising a vertically extending work shaft having an arm projecting therefrom, a two part horizontally extending drive shaft, one of said shaft parts having an endwise movement and a shouldered portion, clutch members mounted on the adjacent end portions

of the shaft ends to operatively and detachably connect the shaft ends together, a resilient and cranked connection between the endwise movable shaft part and the work shaft arm for transmitting a rotary movement of the drive shaft to a reciprocal and rocking movement of the work shaft and to also maintain the clutch members in engagement with each other, and means for engaging the shouldered portion of the shaft part to disengage one clutch member from the other.

8. A washing machine mechanism, comprising a vertically extending work shaft having an arm projecting therefrom, a two part horizontally extending drive shaft, one of said shaft parts having an endwise movement and a shouldered portion, clutch members mounted on the adjacent end portions of the shaft ends to operatively and detachably connect the shaft ends together, a resilient and cranked connection between the endwise movable shaft part and the work shaft arm for transmitting a rotary movement of the drive shaft to a reciprocal and rocking movement of the work shaft and to also maintain the clutch members in engagement with each other, and a reciprocal controlling member having a wedge shaped portion which engages the shoulder of the endwise movable shaft part to disengage one clutch member from the other.

9. A washing machine mechanism, comprising a support having a hinged member, a bearing bracket mounted on the support, a bearing bracket mounted on the hinged member and movable with said hinged member, a driving shaft section journaled in the support bearing, a driving shaft section journaled and endwise movably mounted in the hinged member bearing, clutch members mounted on the adjacent end portions of the shaft ends, a work shaft extending through the hinged member and having a projecting arm, a resilient and cranked connection between the endwise movable shaft section and the work shaft arm for imparting a reciprocal and rocking movement to the work shaft and to hold the clutch members yieldingly in engagement with each other, and means for disengaging one clutch member from the other to permit the movement of the hinged member.

10. A washing machine mechanism, comprising a support having a hinged member, a bearing bracket mounted on the support, a bearing bracket mounted on the hinged member and movable with said hinged member, a driving shaft section journaled in the support bearing, a driving shaft section journaled and endwise movably mounted in the hinged member bearing, clutch members mounted on the adjacent end portions of the shaft ends, a work shaft extending through the hinged member and having a projecting arm, a resilient and cranked con-

- nection between the endwise movable shaft section and the work shaft arm for imparting a reciprocal and rocking movement to the work shaft and to hold the clutch members 5 yieldingly in engagement with each other, a controlling member support extending adjacent the endwise movable shaft section, a controlling member slidably carried by the controlling member support and having 10 a wedge shaped portion for disengaging one clutch member from the other to permit movement of the hinged member.
11. A washing machine mechanism, comprising a support having a hinged member, 15 a two part driving shaft mounted on the support and the hinged member, clutch members mounted on the adjacent end portions of the shaft ends to permit movement of the hinged member when the clutch members 20 are disengaged by an endwise movement of one of the clutch members, a pounder shaft carried by the hinged member and having a resilient and cranked connection with the driving shaft for transmitting motion from one shaft to the other and 25 for maintaining the clutch members in engagement with each other, and means for moving one of the clutch members endwise to permit movement of the hinged member.
- 30 12. A washing machine mechanism, comprising a support having a hinged member, a two part driving shaft mounted on the support and the hinged member, clutch members having tapered rectangular engaging 35 portions mounted on the adjacent end portions of the shaft ends to permit movement of the hinged member when the clutch members are disengaged by an endwise movement of one of the clutch members, a 40 pounder shaft carried by the hinged member and having a resilient and cranked connection with the driving shaft for transmitting

ting motion from one shaft to the other and for maintaining the clutch members in engagement with each other, and means for 45 moving one of the clutch members endwise to permit movement of the hinged member.

13. A washing machine mechanism, comprising in part, a work shaft having a projecting arm, a drive shaft extending at an 50 angle thereto, an arm fixedly mounted on one end of the drive shaft, another arm pivotally mounted on the end portion of the drive shaft and having a ball and socket connection with the arm of the work shaft, and a 55 yielding means interposed between the two arms of the drive shaft.

14. A washing machine mechanism, comprising in part, a work shaft having a projecting arm, a drive shaft extending at an 60 angle thereto, an arm fixedly mounted on one end of the drive shaft, another arm pivotally mounted on the end portion of the drive shaft and having a ball and socket connection with the arm of the work shaft, 65 and a yielding means interposed between the two arms of the drive shaft, for maintaining the pivoted arm operatively connected to the work shaft arm and to impart an endwise yielding tendency to the drive shaft. 70

15. A washing machine mechanism, comprising in part, a work shaft having a projecting arm with a spherical end, a drive shaft extending at an angle thereto, an arm fixedly mounted on one end of the drive 75 shaft, another arm pivotally mounted on the drive shaft end between the fixedly connected arm and the work shaft arm and having a socket into which the spherical end of the work shaft arm extends, and a coiled 80 spring interposed between the pivoted arm and the fixedly connected arm.

In testimony whereof, I affix my signature.
HERMAN C. DOMAN.
